Primary Examiner — Anhdao Doan*(74) Attorney, Agent, or Firm* — Osha Liang LLP(57) **CLAIM**

The ornamental design for a medical X-ray equipment, as shown and described.

DESCRIPTION

FIG. 1 is a perspective view showing a front side, a left side, and a top side of medical X-ray equipment according to the invention.

FIG. 2 is a front view of the design according to the invention.

FIG. 3 is a rear view of the design according to the invention.

FIG. 4 is a left side view of the design according to the invention.

FIG. 5 is a right side view of the design according to the invention.

FIG. 6 is a top view of the design according to the invention.

FIG. 7 is a bottom view of the design according to the invention; and,

FIG. 8 is a perspective view showing a front side, a left side, and a bottom side of medical X-ray equipment according to the invention.

The broken lines in the drawings illustrate portions of the medical x-ray equipment that form no part of the claimed design.
